Inventor:
L. E. Whipple,
By his Atty.
P. T. Dodge.

UNITED STATES PATENT OFFICE.

LEANDER E. WHIPPLE, OF NEW YORK, N. Y.

PLIERS.

SPECIFICATION forming part of Letters Patent No. 393,494, dated November 27, 1888.

Application filed January 25, 1888. Serial No. 261,866. (No model.)

To all whom it may concern:

Be it known that I, LEANDER E. WHIPPLE, a citizen of the United States, residing at New York, in the county of New York and State of New York, have invented certain new and useful Improvements in Pliers, of which the following is a full, clear, and exact description.

This invention relates to an improvement in wire-working tools, and more particularly to 10 that class of tools represented in Letters Patent of the United States, No. 347,675, granted to me on the 17th day of August, 1886, consisting of a pair of pliers having each of its 15 jaws formed to grasp the end of a wire, and provided with the opposing grooves, through which the body of the wire passes loosely, in order that its end may be wound thereon.

This invention consists in providing such a tool or its equivalent with a clamp pivoted to 20 one jaw and adapted to approach and engage the opposite jaw in a lateral direction.

In the accompanying drawings, Figure 1 is 25 a perspective view of a pair of pliers with my invention applied thereto in its preferred form. Fig. 2 is a perspective view of the forward portion of the same. Fig. 3 is a modification.

Referring to the drawings, A represents a wire-fastening tool similar in construction to that represented in my Letters Patent before 30 referred to, provided with the opposing recesses for the body of the wire, and having the inner surfaces of its jaws provided with the roughened portions between which the end of the wire is held.

35 B represents a threaded bolt pivoted to the lower jaw, a', of the pliers in any suitable manner, preferably by a pin, a², fixed in open slot in the jaw and passing through a perforation in the bolt. In the opposite jaw, a, a corresponding open slot, d, is formed large enough 40 to admit the bolt B. e e' represent lugs or projections on the upper jaw, on each side of the slot d. A portion of the surface of these lugs is beveled or inclined in opposite directions, 45 and they are provided with the pins or stops e² and e³, the purpose of which will hereinafter appear.

C represents a nut or handle, tapped to receive the bolt B. By threading the bolt the 50 device is adapted for adjustment to wires of different thicknesses. Though this is the pre-

ferred form, it is not essential—as, for instance, the bolt may be smooth on its peripheral surface, as shown in Fig. 3, with a head, g, formed thereon. By providing the jaws with 55 the open slots the clamp can be placed in an operative position in engagement with the jaws after the tool has been slipped over the body of the wire and its end grasped between them.

60 The operation of the device is as follows: The tool being in the position shown in Fig. 2, it is slipped over the body of the wire, which is embraced within the transverse groove, and the end of the wire grasped between the roughened surfaces. The nut or handle C is then turned on the bolt until it is far enough advanced thereon to touch the upper surface of the upper jaw. When the nut is in its proper position on the bolt, it is turned bodily on its 70 pivot a² up into the slot d, the nut passing between the lugs e' and e. The nut is then turned, by which movement it is caused to ride up the inclined surfaces of the lugs, thereby powerfully compressing the jaws together upon the end of the wire in the manner of a vise. The nut is limited in its motion on the lugs e e' by the stops or pins e² e³ thereon.

75 While I have shown and described a construction best adapted for carrying out my invention, it is to be understood that it is susceptible of various modifications within the range of mechanical skill.

Having thus described my invention, what I 80 claim is—

85 1. The wire-fastening tool provided with the clamp pivoted to one jaw and adapted to approach and engage the opposite jaw in a lateral direction, whereby the clamp may be placed in an operative position subsequent to closing 90 the jaws on the wire.

2. In a wire-fastening tool, the opposing jaws a a', the open slots therein, the bolt B, pivoted in the slot in one of said jaws and adapted to enter the slot in the opposite jaw, 95 its operating nut or handle, and the lugs e e'.

3. In a wire-fastening tool, the opposing jaws a a', the open slots therein, the threaded bolt B, pivoted in the slot in one of the jaws, and its operating nut or handle.

100 4. In a wire-fastening tool, the opposing jaws a a', the open slots therein, the bolt B,

pivoted in the slot in one of the jaws, its operating nut or handle, the inclined lugs $e\ e'$, and the stop-pins $e^2\ e^3$ thereon.

5. In a wire-fastening tool, the pivoted arms forming jaws $a\ a'$, the open slots therein, the two opposing notches, and the grasping-surfaces, in combination with the bolt B, pivoted in the slot in one jaw, its operating-handle, and the inclined lugs $e\ e'$ on the opposite jaw.

In testimony whereof I hereunto set my hand, 10
this 7th day of November, 1887, in the presence
of two attesting witnesses.

LEANDER E. WHIPPLE.

Witnesses:

W. H. WAYNE,
W. C. REID.
